ATTORNEY.

UNITED STATES PATENT OFFICE.

EDWARD S. RAFF, OF CANTON, OHIO.

INKSTAND.

SPECIFICATION forming part of Letters Patent No. 445,201, dated January 27, 1891.

Application filed October 29, 1890. Serial No. 369,681. (No model.)

To all whom it may concern:

Be it known that I, EDWARD S. RAFF, a citizen of the United States, and a resident of Canton, county of Stark, State of Ohio, have 5 invented a new and useful Improvement in Inkstands, of which the following is a full, clear, and exact description, reference being had to the accompanying drawings, making part of this specification.

10 My invention relates to improvements in an article of manufacture; and it consists in providing in an inkstand a fountain or receptacle to hold ink, that may be so balanced or poised as to yield or swing when the pen is 15 placed in the stand, which movement will cause a supply of ink to flow from the body of the fountain to the pen and back into the fountain when the pen is removed, by which a supply of fresh ink is always provided for 20 the pen and the whole body of ink in the fountain moved each time the pen is inked, by which movement the ink is prevented from "settling," and as a result of such frequent movement is always in order for use.

25 With these ends in view my invention consists of certain features of construction and combination of parts, as will be hereinafter described, and pointed out in the claims.

Figure 1 of the accompanying drawings is 30 a side elevation, partly in section, of an inkstand illustrating my invention. Fig. 2 is a plan view, and Fig. 3 a perspective of a fragment of the upper portion of the fountain and bail.

35 A is the base, which may be made of any suitable material, having side frames B and at the top portion of said frames a cross-bar C.

A fountain or ink - holder D, preferably made of glass, is provided, having a hollow 40 body portion a, a neck portion b, projected outwardly and upward, about the upper end portion of which is provided a screw-thread c, and on the top portion of the body D is provided a flanged aperture d, to which is fitted

45 a metal cap f. A mouth-piece E, made, preferably, of hard rubber and of the form shown in the drawings, is provided, said piece having upwardly-projected walls h, a downwardly-projected neck portion m, having a screw 50 k similar and adapted to the thread c on the neck of the fountain, and a central and down-

wardly-projected tube portion n, the aperture of which is small, as shown.

On the top and side portions of the inkfountain D and diametrically opposite are 55 provided bails F, having on their under side portion corresponding notches p. The bar C is passed through the bails and into the perforations provided at the top of the side frames B, the bails to rest on the bar to support the fountain in a swinging position, and the bar in corresponding notches.

To arrest the downward movement of the front portion of the fountain, a stop G is provided, consisting of a button-headed screw, to 65 be turned into or out of the base A, the head to stand at the desired height to arrest the downward movement of the fountain.

In operation a sufficient amount of ink is 70 passed through the aperture provided therefor into the fountain to immerse or cover the end of the tube n to a point indicated by the dotted line, the swing or tip of the fountain to be regulated by moving the suspending bails forward and back over the supporting 75 bar C, the bar to rest in corresponding notches, and thus adjust or regulate the swing of the fountain to the amount of ink therein, so as to prevent an excess rising through the tube n, and by keeping the end of said tube constantly immersed air-bubbles rising above 80 the tube into the mouth E will be prevented, and by the swinging movement of the fountain the ink is not liable to "settle," as in the case with a stationary fountain or one that 85 is not so moved at every inking of the pen. To ink the pen it is placed in the mouth E, and by a gentle downward pressure the fountain will swing about the bar C, the front portion down and the rear portion up, at 90 which instant ink will flow from the fountain up through the tube n into the mouth E, and when the pen has been inked and removed the fountain will swing back into its normal position, as shown in Fig. 1. 95

Having thus fully described the nature and object of my invention, what I claim as new, and desire to secure by Letters Patent, is—

1. As an article of manufacture, an inkstand having a support consisting of a base 100 A and side frames B, said frames having at their top portion a cross-bar C, and a fount-

ain D, having bails notched to engage said bar, by which said fountain is supported to swing about said bar and adapted to be moved back and forward to balance or adjust the fountain thereon, substantially as described, and for the purpose set forth.

2. In an inkstand, the supporting-frame described and an ink-fountain having notched bails by which said fountain is supported to swing on said frame, and a stop G to arrest

the downward movement of the fountain at a desired point, substantially as described, and for the purpose set forth.

In testimony whereof I have hereunto set my hand this 17th day of October, A.D. 1890. 15

EDWARD S. RAFF.
